CARBURETOR

William E. Leibing, Detroit, Mich., assignor to Leibing-Fageol Company, Detroit, Mich., a partnership composed of F. R. Fageol, Ravenna, Ohio; R. D. Fageol, Detroit, Mich.; Jessie M. Fageol, Ravenna, Ohio; W. E. Leibing, Detroit, Mich.; and D. C. Farnsworth, Veterans Hospital, San Fernando, Calif.

Application October 1, 1940, Serial No. 359,282

8 Claims. (Cl. 261—34)

The present invention relates to improvements in carburetors for internal combustion engines, and more particularly to that class of carburetors in which the throttle valve for controlling the flow through the fuel conduit is positioned on the atmospheric side, or up-stream side, of the jets controlling the flow of fuel through the device, such a carburetor being sometimes known as the anterior throttle type. However, it is to be understood that a number of the features disclosed herein are applicable as well to carburetors of any type.

Carburetion of the type described above has always been difficult and complicated. In an effort to solve the problems of such a carburetor, the prior art has resorted to complicated metering devices employing extremely accurately machined metering pins and like means, all of which materially increase the costs of manufacture and the upkeep. Present day standard carburetors have also become very complicated in principle to a point where the average mechanic fails to understand said principle and is therefore entirely unable to make any correction or repair to the instrument. Factory-trained men who are equipped with jets of different sizes and substitute parts of different characteristics are, perhaps, the only personnel who can be trusted to make a satisfactory adjustment on a carburetor.

Present day accelerating pumps, used to cover the "hesitation" stage in a carburetor when the throttle is opened, are not entirely satisfactory in that their points of discharge into the carburetor conduits are often at points where the fuel must pass the throttle valve before entering the engine and be subject to a number of eddy currents. Furthermore, the arrangement of the pump is sometimes such that fuel is constantly being sucked therethrough during operation of the engine, unless specific preventive means in addition to the normal pumping mechanism is provided. This necessitates additional expense and more complications.

In prior carburetors, reliance has been principally had upon the venturis employed therein to insure the proper mixture at all throttle positions. By reason of the inherent characteristics of such venturis as regards their development of kinetic energy, they cannot be relied upon except in full open throttle position. In all other positions, their performance is virtually indeterminable. In an effort to meet this defect in the venturis, metering devices have been adopted which are both complicated and expen-

sive, and at best have not been entirely satisfactory.

In overcoming the aforesaid disadvantages, it is a major object of this invention to provide a carburetor having novel and relatively simple and inexpensive metering means whereby all so-called metering pins, their tubes, and like complicated and expensive devices, are eliminated.

A further object of this invention is the provision of a carburetor having novel means for controlling the flow of fuel wherein the effect of the variable characteristics of the venturi are eliminated, except at stages of operation wherein the venturi can be depended upon to function consistently and correctly, as at wide open throttle.

A further object of this invention is to provide a novel carburetor wherein the air-fuel ratio for any given position of the carburetor throttle can be made richer or leaner without influencing any other position of the throttle.

Still a further object of this invention is the provision of a novel carburetor having means to better atomize the fuel and obtain a more correct mixture of fuel and air for securing better economy.

A further object of this invention is to provide a novel carburetor of a design to eliminate the discharge of obnoxious gases and unburned fuel from the exhaust of an engine equipped with such a carburetor.

Still a further object of this invention is the provision of novel idling means for a carburetor whereby a more economical and efficient flow of fuel to the engine at idling speeds, and in a condition better to be consumed, is secured.

A further object of this invention is the provision of a novel carburetor having a booster pump associated with the idling means whereby the function normally assumed by the conventional accelerator pump is taken over by the idling jet in more efficient manner, and a number of parts in the carburetor, hitherto considered necessary, eliminated.

Referring to the drawings

Figure 1 is a plan of a carburetor embodying the present invention taken on the line 1—1 of Fig. 2.

Fig. 2 is a section taken on the line 2—2 of Figure 1 illustrating in detail the metering mechanism and the fuel pump.

Fig. 3 is a section taken on the line 3—3 of Figure 1 showing a cross-section of the carburetor conduit and the relation of the idling jet to the carburetor throttle.

Fig. 4 is a section taken at right angles to the section of Fig. 3, and on the line 4—4 of Figure 1, illustrating the manner of utilizing the carburetor throttle shaft as a part of the fuel feeding means for the main jet of the carburetor in conjunction with the metering mechanism.

Fig. 4a is a section similar to the section appearing at the right side of Fig. 4, except that the fuel metering mechanism is shown in the position corresponding to open position of the throttle.

Fig. 5 is a front elevation of the preferred form of plug used to form the idling jet.

Fig. 6 is a side elevation of the plug of Fig. 5 with the plug rotated 90 degrees.

Fig. 7 is an enlarged section of the plug as it appears in Fig. 3.

Fig. 8 is a section taken on the throttle shaft coincident with the connection of the bore in the throttle shaft with the passage leading to the main jet, and showing the position in which the main jet is disconnected from its fuel supply, as occurs in closed position of the throttle.

Fig. 9 is a view similar to Fig. 8 showing the throttle shaft rotated to a position where the main jet is connected to the fuel supply.

The present invention is described for the purpose of illustration in connection with a carburetor of the so-called down-draft type, the arrows indicating the direction of the flow of fluid through the carburetor. In all the figures, corresponding numbers are employed to indicate like parts.

Referring to Fig. 3, which illustrates the fuel conduit of the carburetor, a housing 11 is provided with a flange 12 formed with apertures 13 and 14 therein for attachment to the intake section of an engine intake manifold (not shown) in well known manner. Directly above flange 12 and either made integral with housing 11, or arranged for insertion therein, both arrangements being conventional practice, a venturi 15 is provided with the usual shaped orifice centrally located within housing 11. Directly above venturi 15 is the central bore 16 of the conduit in which is positioned a butterfly valve 17. Valve 17 is mounted for oscillation in conduit 16 by means of a shaft 18, the valve being secured thereto by suitable fastening means, such as screws 19.

Adjacent the upper righthand edge, or leading edge, of throttle 17 when in its closed position, as shown in Fig. 3, housing 11 is formed with a horizontally extending boss 21 with an aperture 20 for receiving an idling jet plug 22, a detailed description of which will be later given. A cover or upper housing 23 is positioned above housing 11, and is arranged to be secured thereto by suitable flanges and fastening means not shown. Housing 23 is provided with an air bleed passage 24 which registers with a passage 25 in housing 11 to connect a passage 26 in housing 23 with the aperture formed in boss 21. A needle valve 27 is mounted on a boss 28 formed on housing 23, as shown in Fig. 3, to control the passage 26. A spring 29 is preferably provided in conjunction with valve 27 to form a frictional lock and maintain the valve in its adjusted position.

Aperture 20 in boss 21 is connected by a conduit 31 to the bottom of a float chamber 32 (Fig. 2) formed on one side of housing 11 as shown in Fig. 1, and disposed substantially entirely to one side of shaft 18, as shown in Fig. 1. The upper portion of the float chamber is subject to atmospheric pressure by reason of a passage 40 opening into section 23 of the carburetor conduit (Fig. 4).

As shown in Fig. 1, throttle shaft 18 extends into the float chamber and terminates at a point approximately midway thereacross. A metering device, or arm, 33 (Fig. 2) is secured to the float chamber end of shaft 18 in a manner to rotate therewith, arm 33 being formed in what might be called a bent-arm fashion, the elbow 35 of which is always pointed outwardly and downwardly when viewed as in Fig. 2. Bent-arm 33 comprises an upper arm section 34 extending from shaft 18 to elbow section 35, this upper arm section being substantially horizontal as viewed, and a forearm section 36 extending substantially vertically from elbow section 35. A passage 37 is formed within upper arm section 34, passage 37 connecting with a passage 38 in forearm section 36. Forearm 36 is preferably formed in a shape approximating the arc of a circle which has as its center shaft 18 to insure the entrance and exit of forearm 36 into the fuel at the same point at all times, namely, at the center of the chamber where the change in level of the fuel by reason of the vibration and various inclinations of the vehicle on which the carburetor is used is a minimum. Passage 38 in forearm section 36 is preferably formed by a series of straight bores, as shown, to facilitate manufacture, the bores being plugged at their outer ends by plugs 39 and 41.

Preferably a series of spaced metering apertures 42 which constitute metering means, shown for illustration to be 13 in number, are provided in forearm section 36 communicating with the space in the float chamber and with passage 38. While a series of successive apertures have been illustrated, it is to be understood that a series of slots, one long slot, or openings of other shapes, may be provided as found desirable in certain specific installations.

As shown in Fig. 4, throttle valve shaft 18 is bored at its right end, or the float chamber end, to form a main fuel conducting passage 43 extending for some distance within the shaft to a point above a bore or fuel passage 44 formed in the housing 11. To connect bores 43 and 44, a cross fuel passage 45 is provided in shaft 18, as shown in Figs. 8 and 9, passage 45 being positioned to be in alignment with vertical passage 44 in housing 11 when throttle valve 17 is in wide open position, as shown in Fig. 9, and to be out of alignment and close the connection between bores 43 and 44 when the throttle valve is in closed position, as shown in Fig. 8. To vary the point at which the connection is made between 43 and 44, a second cross drilling 46 is preferably made in shaft 18, the size and position of which may be varied to provide for a connection between bores 43 and 44 at any desired point in the opening of throttle valve 17.

Vertical bore 46 terminates in a cross passage 47 which is preferably enlarged at its left end where it opens into conduit 16 to receive one end of a curved tube 48, the lower or outlet end 49 of which is centrally located at the point of highest velocity in venturi 15, the tube 48 and its end 49 becoming the main jet of the carburetor. Tube 48 is preferably secured in passage 47 as by swaging, the tools for which may be conveniently introduced through a hole normally sealed by a plug 51, as shown in Fig. 4.

Referring to Figs. 1 and 2, a pump cylinder 52 is provided in float chamber 32 of housing 11, a check valve 53 of conventional character being provided at the lower end of pump cylinder 52 whereby fuel is free to pass out of the cylinder

into tube 31 leading to the idling jet, but cannot flow back into the cylinder. Tube 31 leading to the idling jet is connected to the housing below check valve 53 in fluid tight relationship, a plug 54 being preferably provided to facilitate assembly and the cleaning of the parts.

A pump piston 55 is provided to reciprocate vertically in cylinder 52, the piston being provided with a piston rod 56 working in a guide 57 mounted in the upper part of the float chamber. A disc 58 is secured to piston rod 56. A spring 59 of the helical compression type, and preferably tapered, is provided between disc 58 and the upper part of the float chamber housing, this spring always tending to urge pump piston 55 toward the bottom of pump cylinder 52 and inject fuel through tube 31 into the idling jet and from there into conduit 16.

Piston 55 is formed with a plurality of bores 61 and a check valve 62 of the disc type, whereby fuel may freely pass from the float chamber through bores 61 and out of passage 31, but cannot pass in the opposite direction. Obviously when piston 55 is moved downwardly by spring 59, check valve 62 closes, and the fuel in cylinder 52 is forced out through conduit 31. When piston 55 is stationary, check valve 62 will be open and a free flow of fuel through bores 61 will be assured.

Forearm section 36 of metering device or arm 33 is provided with a lug or abutment 63 which is positioned to engage disc 58 and raise piston 55 against the force of spring 59 when the throttle goes to closed position, abutment 63 swinging downwardly when the throttle is opened, and permitting discs 58 to lower and fuel to be forced into tube 31 by reason of the pressure of spring 59. As lug 63 does not engage disc 58 during the lower portion of the swing of arm 33, the pump is obviously operated to pump fuel only during the initial stage of movement of arm 33 corresponding to the initial opening movement of the throttle. When the throttle shaft is rotated to close the throttle, arm 33 swings clockwise, whereupon lug 63 engages disc 58 of the pump and raises the piston, thus reloading the pump.

Adjacent to and preferably equidistant from metering device 33 is a pair of floats 64 and 65 secured to a U-shaped lever 66. Lever 66 is pivoted on a shaft 67 in the float chamber which, in turn, is supported by a bracket 68 attached to the carburetor housing. The upper surface of lever 66 contacts the lower end of a vertically reciprocal needle valve 69 which operates in a removable plug 70 having a valve seat 71, this assembly acting to maintain a constant level of fuel within float chamber 32, and either shut off or admit fuel, as the necessity may arise in the operation of the engine. A fuel line, not shown, is preferably attached at threaded hole 72, the passage of fuel therefrom being governed by needle valve 69.

Referring back to plug 22 which is used to form the idling jet, and referring specifically to Figs. 5, 6, and 7, which are enlarged views of the plug as viewed in Fig. 2, the plug is formed roughly as a solid cylinder, the left end thereof, as viewed in Figs. 5, 6, and 7, being provided with a transverse slot 73 which extends inwardly to a point 74 (Fig. 6) and communicates with a metered orifice 75 leading to a large bore or passage 76 within the interior of the plug. The plug is recessed to provide an annular recess 77 and an annular recess 78 which form annular chambers 79 and 81, respectively, (Fig. 3) with the inner walls of

aperture 20 in boss 21, the plug being of a size such that chambers 79 and 81 are sealed from one another in fluid tight relation. As shown in Fig. 7, slot 73 extends back into the annular recess 78.

5 17. Bore 76 is connected to annular recess 78 by transverse bores 82.

At its right end, bore 76 is preferably threaded to receive a screw 83 which is normally tightened to close the outer end of the bore, and can be 10 removed to readily clean the plug and remove any obstructions in the idling jet. As compared with prior carburetors wherein the idling jets have been virtually hidden away in the interior of the carburetor, and any clogging thereof has 15 necessitated a complete disassembly of the device, the idling jet of the present invention is extremely easy to clean. The only thing that must be done is remove screw 83 and access is readily had to the interior of the jet.

20 By reason of slot 73, annular chamber 79 is in metered relation with the atmosphere at its left side through the area of slot 73 up-stream of the edge of throttle valve 17, and is in metered relation with the atmosphere through the passages 24, 25, and 26.

When plug 22 is assembled with a carburetor, annular chamber 81 communicates with the upper end of conduit 31 (Fig. 3), chamber 81 thus becoming a fuel chamber from which raw 30 fuel is fed in metered relation through metering jet 75 into slot 73. By reason of the metered atmospheric air present in chamber 79 and slot 73, air is immediately mixed with the fuel discharged from jet 75, and the resultant air and fuel mixture discharged adjacent the leading edge of the carburetor throttle valve 17.

By reason of this arrangement, the fuel and air to be discharged from the idling jet are not mixed until just prior to their discharge from 40 the jet. This is of advantage compared with the prior constructions wherein attempts have been made to mix the fuel and air sometime prior to their actual discharge from the idling jet, and the fuel and air mixture has been required to travel through a number of tortuous passages. Because of such passages, the fuel and air mixture has tended to separate, as a result of which a series of globules of fuel separated by air pockets have been discharged from the idling jet rather 50 than a homogeneous mixture of fuel and air.

When assembled, carburetor throttle valve 17, or rather, the leading edge thereof, lies adjacent the left end of plug 22, and in its furthermost closed position will appear approximately as 55 shown in Fig. 7, at which point it will be noted that a small amount of transverse slot 73 is located down-stream from throttle 17, while a far greater area of slot 73 is located on the up-stream side of the throttle, and therefore open to atmospheric pressure. When the throttle goes from a full closed to a full open position, it will 60 traverse slot 73 and thereby simultaneously increase the amount of the slot down-stream or below the throttle and decrease the amount of slot above or up-stream of the throttle.

65 It will be noted in the carburetor as described an idling jet is provided in combination with an anterior throttle, the main supply jet under normal running conditions being positioned between the throttle and the intake of the engine adjacent the venturi.

Method of operation

If it be assumed that the carburetor as thus far described is assembled with an internal com-

bustion engine of the spark ignition type, and that the engine is running at the idle or closed throttle position, and that fuel is being supplied under pressure through connection 72, floats 64 and 65 will function to maintain the fuel level in float chamber 32 constant at the dotted line marked FL in Fig. 2. As cylinder 52 is below this level, the cylinder will be entirely filled with fuel, which fuel will pass through conduit 31 to the idling jet.

With the engine idling and the throttle valve 17 in its furthermost closed position, as shown in Fig. 3, a vacuum of approximately 18 to 20 inches of mercury will exist down-stream of the throttle in conduit 16. The area of transverse slot 13 down-stream of the throttle valve will therefore be subject to such vacuum which will be effective through slot 13 upon annular chamber 79 and through jet 75 and transverse bores 82 upon annular chamber 81. However, as the upper exposed portion of slot 13 is of a greater area than the lower portion, and it is up-stream of the throttle valve, and therefore subject to substantially atmospheric pressure, considerable air enters slot 13 and relieves this vacuum to some extent. Additional air is also free to enter by way of passages 24, 25, and 26, and further relieve the vacuum, this amount of air being regulated by the adjustment of screw 27 to a point where just sufficient fuel is drawn from jet 75 to meet the requirements of the engine at this phase of operation. Any shutting off or diminishing of the air admitted by way of aperture 26 will increase the amount of fuel drawn from jet 75, and any increase in the amount of air admitted by hole 26 will correspondingly decrease the amount of fuel drawn through jet 75.

Any movement of valve 11 towards an open position will change the relation of the portions of slot 13 exposed up-stream and down-stream of the valve, and thereby increase the proportion or amount of the slot exposed to the high vacuum down-stream of the valve and decrease the amount of the slot exposed to atmospheric air. Thus the vacuum acting on the jet 75 will be increased. Correspondingly, the amount of fuel fed therethrough will be increased and the requirements of the engine met.

This arrangement possesses advantages not found in the prior art. In the prior art, it has been customary to use but one groove or chamber connecting with the idling jet into which single groove is fed both the raw fuel and the air. Furthermore, the metering orifice or other metering means for the raw fuel is often removed a considerable distance from the point of discharge of the idling jet into the carburetor conduit. It has been found by actual experiment that such a design tends to make any single annular chamber perform as a collector in which a drop or two of fuel first collects and is then discharged as raw fuel rather than as an emulsion. With the present arrangement, the raw fuel never enters the annular chamber 79, but is delivered direct to slot 13 wherein the space is so confined, and the distance it is to travel so short (before being discharged into the main bore of the carburetor) that there is no possible chance for separation of the fuel and air, or accumulation of raw fuel. The mixture thus discharged is homogeneous, and is fed in an even, continuous flow which greatly improves the engine performance at idling.

Referring back to Fig. 2, it will be noted that during the above described idling operation, all

the apertures 42 in the forearm section 36 of the metering device are well above the float level FL and that any leakage through the jet 49 by reason of the vacuum effective thereon can only draw air at atmospheric pressure from the upper portion of the float chamber 32. Furthermore, when the carburetor throttle valve is in a position whereby the engine is idling, shaft 18 is in the position shown in Fig. 3, whereby passage 44 and consequently jet 49 are completely shut off from the fuel supply.

To further insure against the introduction of fuel under idling conditions through jet 49, and possibly around the portion of the housing supporting the right end of shaft 18, as viewed in Fig. 4, a series of annular recesses 84 are cut in shaft 18 at positions to register with passages 85 leading to the atmosphere. This bleeding of atmosphere in and around the bearing supporting shaft 18 prevents the sucking in of any undesired fuel into the carburetor conduit around the bearing.

To further prevent any undesirable siphoning action by reason of the connection of jet 49 to the float chamber, the end of bore 43 in shaft 18 is preferably plugged by a plug 86 which has a small metered orifice 87 therein open to the area of the float chamber above the fuel level, which is open, in turn, to the atmosphere. Orifice 87 permits the entry of a restricted amount of air, and prevents any siphoning action.

The above described idling arrangement has been found to be further advantageous inasmuch as when the fuel at idling is discharged from the down-stream portion of slot 13, it is at such a point that the fuel must pass the venturi 15, which is positioned between the idling jet and the carburetor outlet. From actual observation through glass manifolds, it has been found that with the present invention, venturi 15 operates to even out the fuel flow, which includes both air and fuel, and to discharge it in a uniform, invisible, homogeneous mixture. In present standard carburetors of the interior throttle type, like observations show that the idling mixture is discharged unevenly, with the raw fuel following one path, and the air following another path. The manner in which the fuel is mixed and thereafter handled in the present invention is of utmost importance in providing gas-free operation during all running conditions, and also during decelerating phases, as when the car is driving the engine, as occurs in descending a hill when the engine at closed throttle is being used as a brake.

Taking up the second phase of operation of the carburetor, as the engine goes from idling position to a phase of operation where the throttle valve is moved to a further open position, the operation above described applies equally well to the first stages of movement of the carburetor throttle valve, and hence will not be repeated.

As the throttle is opened from closed position towards an open position, the area of slot 13 down-stream of the throttle valve will be increased, causing a higher vacuum to be effective upon jet 75, while at the same time the area of slot 13 existing up-stream of the throttle is decreased, thus further increasing the vacuum effective upon jet 75. Such increase in vacuum results in increased fuel flow, and assuming that the size of jet 75 and the width of slot 13 have been properly selected and coordinated, the throttle valve may continue to open until the entire area of slot 13 has been transferred to

the down-stream side of the throttle valve. During all stages of this movement, the mixture will remain correct as regards the air-fuel ratio, and the operation of the engine will be correct. As slot 73 becomes fully exposed to the high vacuum down-stream of the throttle valve, the maximum amount of fuel is being drawn from jet 75. If no further means were employed, this position of the carburetor throttle would constitute a limit beyond which the valve could not open without radically affecting the air-fuel ratio to a degree where the engine would not function. However, coincident with the throttle valve arriving at this position, the first hole of series 42 in the forearm section 36 dips into the fuel of the float chamber, and a small amount of fuel is added through jet 49 to the high velocity air passing through the carburetor, the connection between passage 44, slot 46 and passage 45 having been made by the valve moving toward open position.

Further movement of the throttle valve toward open position immerses additional holes 42 below the fuel level, and increases the capacity of the forearm section 36 for fuel. Thus, more and more fuel is fed to the mixture emerging from jet 49, until the throttle valve is wide open, and all holes of the 42 series are being fed fuel. It is to be understood that in partially open position of the throttle valve, where all of the holes 42 are not immersed, a certain quantity of air determined by the number of holes 42 above the fuel level in the float chamber may be drawn into the passages 38 and 37 and mixed with the fuel being sucked therein. This quantity of air will be determined by the size of holes 42 and the number thereof that are immersed.

As jet 49 is positioned considerably below the float level in the float chamber, and is in fluid-tight relationship with shaft 18, it is apparent that if the engine were left at wide open throttle and the ignition shut off, or if a heavy load sufficient to bring the engine down to practically idling speed were imposed on the engine, then in both cases jet 49 would siphon fuel from the float chamber. Such siphoning is prevented by the metered orifice 81 in the right end of shaft 18, which permits the leak of atmosphere into the fuel line at a point well above the fuel level in the float chamber, and effectively prevents such siphoning action.

It is further apparent from the above that at any position of the throttle valve after the first hole in the 42 series has been submerged in the fuel, a rich, a lean, or the correct amount of fuel can be secured without in the least upsetting some position further along in the scale.

Referring to the final phase of operation, or the means functioning to supply the various types of mixtures required by change in load conditions without any change of throttle position, a heavy load requires a somewhat richer mixture than a light or no load. If it be assumed that there is a light load with a throttle position equivalent to 3 of the 42 series holes beneath the fuel level, the other 10 holes of series 42 would be delivering a considerable amount of air, and jet 49 would be discharging an emulsion of air and fuel at high velocity.

If the throttle is left at the position where 3 of the 42 series holes are submerged and a load sufficient to almost stall the engine is applied, there will be light flows passing through passage 44 and jet 49, and the 10 holes of the 42 series above the fuel level will be entirely ineffective as regards a supply of air to jet 49 because of the fuel flowing

5 into the interior of the bent arm section by way of the 3 holes of the 42 series below the fuel level. Thus the mixture discharged from jet 49 has been converted from ten parts of air to three parts of fuel (figuratively) to no air and three parts of fuel, so that jet 49 is discharging fuel diluted only by the air admitted by the siphon break 81.

This follows because of the very low vacuum effective through passage 37 upon bore 38, this 10 vacuum being only sufficient to utilize the capacity of the 3 holes of the 42 series immersed below the fuel level. Under such conditions, elbow section 35 which is immersed below the fuel level operates as a liquid seal to prevent the passage 15 of any air from the holes of series 42 above the fuel level into passage 37, and from there into jet 49.

To illustrate this action still further, let us assume the engine is shut off with the throttle valve 20 17 still in the described position. It is readily apparent that the 3 holes of the 42 series below the fuel level will permit the fuel to enter the arm 33 and seal off from the outlet hole 37 the remaining 10 holes of the 42 series so that any resumption 25 of flows in hole 37 towards the shaft 18 must be first of a solid fuel.

The above applies to all positions of the throttle valve up to wide open position, at which point a slightly different operation occurs. Whether the 30 engine be under light load or under heavy load, all holes of the 42 series are below the fuel level in the float chamber, and therefore no change in the output of the metering device as regards the air-fuel ratio can occur. Therefore, it would 35 appear that no correction of mixture as regards load occurs. However, it must be remembered that this occurs only at wide open throttle position, so that for the first time in the operating sequence venturi 15 is really effective as to the 40 kinetic energy developed by jet 49 located at the most advantageous point in venturi 15. The venturi, in controlling for this one position only, has proven itself well able to control the fuel flows within required limits.

In other words, as compared to the operation 45 of a venturi in an interior throttle carburetor wherein the venturi functions in throttled as well as in unthrottled position, and therefore has a range of operation so wide that it includes the well known variable of kinetic energy, to correct 50 which all of the modern carburetor patent history is dedicated, in the present invention the venturi is not in control during throttled positions, and hence its variable characteristics do not enter into the picture. Instead, in the present 55 invention, during throttled positions, vacuum is in control, and therefore the characteristics of the venturi do not affect the air-fuel ratio at these throttled positions to any appreciable extent.

As regards the acceleration phase of the carburetor, practically all present carburetors are 60 designed to run on mixtures which are so lean that any sudden change of the throttle to a further open position results in "hesitation" of the engine until the proper flows in the new position have been established. To overcome this 65 hesitation, practically all modern carburetors, and particularly those used on automobiles, buses, and the like, are equipped with mechanical acceleration pumps usually connected to the throttle rods. Practically all of these pumps discharge on the atmospheric side of the throttle valve, where, due to the interference of parts in 70 the carburetor conduit, eddy currents and other 75

factors, the results are not entirely satisfactory. Furthermore, such arrangements are inclined to draw fuel in running positions, and further means is required to eliminate this drawing of fuel which, of course, requires added structure with its attendant complications and disadvantages.

In the present invention, the idling jet is used as the outlet for the accelerating device, thus accomplishing a considerable saving in parts and machining. Furthermore, no means is required to eliminate flows when not required. In the present device, the pump might better be described as a booster pump on the idling system rather than as a separate accelerating pump. As a result of actual tests, it has been found that the use of the idling jet as a pump discharge jet is far superior to any other arrangement.

It is to be understood that various means of choking, well known to the art, can be employed in combination with the present carburetor for the purpose of starting the engine when cold. As such chokes do not form any part of the present invention, description thereof has been omitted. It is also to be understood that the carburetor throttle valve 17 may also be utilized as a governing valve in accordance with well known practice. In the present illustration, for the purpose of brevity, idling and high speed limiting stops on throttle valve shaft 18 have been omitted as well as the conventional throttle rod mechanism for manually rotating the throttle valve shaft, together with its attendant spring means for normally maintaining the throttle valve in closed position.

A still further advantage of the present invention resides in the ability of the design to use a larger venturi than standard practice, or modern carburation, will permit. Whereas in the standard type of carburetor, an extremely large venturi cannot be used due to the venturi controlling and creating the partial throttle flow of fuel, in the present carburetor, the venturi controls only wide open performance. As an example, a racing venturi could be used with no loss of performance at $\frac{1}{4}$ or $\frac{1}{2}$ throttle, while standard practice for racing carburetors would render the engine extremely poor in operation at speeds of about 20 to 30 miles per hour.

The present invention is also advantageous in that it has been found by actual trial that it is possible to design the carburetor to correctly carbure any engine without changing the carburetor. For instance, it has been found that when the carburetor was worked out for one type of engine, it is possible to transfer it to an engine of an entirely different type and still secure perfect performance.

It is to be understood that the invention may be embodied in specific forms other than that illustrated without departing from the principle or essential characteristics thereof. The embodiments shown are therefore to be considered as illustrative and not restrictive, the scope of the invention being defined by the appended claims rather than the foregoing description and drawings. All modifications and changes which come within the meaning and range of equivalency of the claims are therefore intended to be included therein.

I claim:

1. A carburetor for an internal combustion engine comprising a conduit, a throttle valve in said conduit, a shaft for supporting said valve, a fuel jet in said conduit, a float chamber, said shaft being formed with a fuel passage connected with

said fuel jet, and means to connect said fuel passage to said float chamber comprising a hollow arm connected to said shaft to rotate therewith, and extending outwardly therefrom, a portion of said arm being bent upwardly and being formed with a series of metering openings arranged to be successively immersed in the fuel in said float chamber as said throttle valve is opened.

2. A carburetor for an internal combustion engine comprising a conduit, a throttle valve in said conduit, a fuel jet in said conduit, a float chamber, a shaft to support said throttle valve, said shaft having a passage therein for a portion of its length, means to connect one end of said passage to said fuel jet, and means to conduct and meter fuel into said passage from said float chamber comprising a conduit secured to said shaft to rotate therewith and extending outwardly therefrom, and a second conduit at the end of said first conduit, said conduits being relatively positioned to form a substantially horizontal extending upper arm with a substantially vertical forearm when said throttle is in closed or substantially closed position, the elbow section of said arm being positioned to enter the fuel in the fuel chamber first upon rotation of said shaft in a direction to open said throttle valve, the remainder of said arm being progressively immersed in the fuel as said throttle goes to open position, said forearm section being provided with fuel metering means distributed along its length to receive fuel from said fuel chamber in a manner whereby its capacity for fuel is increased as said throttle valve goes to further open position and said forearm section is progressively immersed in the fuel.

3. The carburetor claimed in claim 2 wherein said fuel metering means on said forearm section is positioned substantially along an arc of a circle with the center of the circle substantially coincident with said throttle valve shaft for causing said metering means to be progressively immersed at substantially the same point in said float chamber as said throttle valve shaft rotates to move the throttle valve to open position.

4. The carburetor claimed in claim 2 wherein a fuel pump is provided with means for normally urging said pump into pumping action, and means is provided on said forearm section to release said means for operating said pump during the initial stages of movement of said forearm section with the opening movement of said throttle.

5. The carburetor claimed in claim 2 wherein said fuel metering means on said forearm section comprises a series of spaced apertures communicating with a central bore whereby the number of apertures available for fuel flow is increased as said section is progressively immersed in the fuel in said float chamber.

6. A carburetor for an internal combustion engine comprising a conduit, a throttle valve in said conduit, a fuel jet in said conduit, a float chamber, a shaft to support said throttle valve and secured thereto to rotate therewith, said shaft having a passage therein, means to connect one end of said passage to said fuel jet, and means to conduct and meter fuel and air into said passage from said float chamber comprising a conduit secured to said shaft and extending therefrom to move with the latter and said throttle, a second conduit secured to the end of said first conduit, said conduits being relatively positioned to form a substantially horizontal extending upper arm with a substantially vertical forearm when said

throttle is in substantially closed position, the elbow section of said arm being positioned to enter the fuel in said float chamber first upon rotation of said shaft in a direction to open said throttle valve, the remainder of said arm being progressively immersed in the fuel as said throttle goes toward open position, said forearm section being provided with fuel metering means to receive fuel and air from said float chamber whereby the proportion of air to fuel is decreased as said throttle 10 valve goes to further open positions and said forearm is progressively immersed in liquid fuel.

7. A carburetor for an internal combustion engine comprising a conduit, a throttle valve in said conduit, a shaft for supporting said valve, a fuel jet in said conduit, a float chamber, said shaft being formed with a fuel passage connected with

said fuel jet, and means to connect said fuel passage to said float chamber comprising a hollow upwardly bent arm, the outer portion of said arm being shaped substantially as an arc of a circle with the center of the circle coincident with said throttle valve shaft, said arm being formed with metering means arranged to be progressively immersed in the fuel in said float chamber as said throttle valve is opened.

8. The combination claimed in claim 1 wherein means is provided to connect said fuel passage with said fuel jet at all positions other than closed position of said valve, and to disconnect said fuel passage from said fuel jet when said 15 throttle is in closed position.

WILLIAM E. LEIBING.
